UNITED STATES PATENT OFFICE

WILLIAM W. SHAKESPEARE, OF SOUTH ORANGE, NEW JERSEY, ASSIGNOR TO ANACONDA SALES COMPANY, OF NEW YORK, N. Y., A CORPORATION OF DELAWARE

APPARATUS FOR APPLYING COATINGS

Application filed December 30, 1929. Serial No. 417,425.

This invention relates to the application of coating materials to sheets or the like and is concerned more specifically with apparatus by which a coating material, such as one which is fluent only when heated, may be applied to a sheet to provide a film of the desired thickness. This apparatus is particularly useful in connection with affixing one sheet to another by an adhesive coating, and an embodiment of the invention suitable for that purpose will presently be described.

The apparatus of the invention includes a heated vessel for the coating material and means such as a roller for applying a film of the coating material to the surface of a sheet. The roller is mounted so that its surface dips beneath the level of the coating material in the tank, and the sheet is led in contact with the roller to receive coating material therefrom. The thickness of the film so applied may be regulated by a doctor blade, preferably controlling the amount of material picked up by the roller, and so mounted that it is maintained substantially at the temperature of the material in the vessel so that the coating material will not adhere thereto. The coated sheet leaving the roller is next engaged by a doctor blade having an interrupted working edge which scrapes all the film from the sheet except along spaced lines corresponding to the interruptions. This doctor blade is also maintained substantially at the temperature of the material in the vessel and for this purpose may be mounted to dip below the surface of the material in the vessel. The blade is preferably of thin sheet metal of good heat conducting properties, such as copper.

The sheet with the spaced lines of coating material is next passed through driven pressing rolls with the sheet to be united to the coated sheet also passing through the rolls and in contact with the coated face of the first sheet. The pressure applied to the rolls forces the sheets into firm contact and spreads the coating material in the spaced lines to cover the entire contacting areas of the sheets. The spacing of the notches in the doctor blade and the depth of the notches determines how much coating material is applied to the

first sheet and the application of the material can be closely controlled so that a good cohesion of the sheets is obtained without the use of an excess of the adhesive coating material.

For a better understanding of the invention reference may be had to the accompanying drawing, in which

Fig. 1 is a view of the apparatus in longitudinal section;

Fig. 2 is a fragmentary face view of a novel doctor blade forming part of the invention;

Fig. 3 is a fragmentary plan view of a piece of material being coated at one stage in the operation.

The apparatus comprises a tank or vessel 10 which contains a supply 11 of the coating material and is heated by a burner 12 when the coating material used is one which is fluent only when heated. Disposed above the tank and, if desired, mounted in bearings 13 on the tank walls is a roller 14 which is so positioned that its peripheral surface dips into the coating material. This roller is mounted for free rotation and, as it rotates, it picks up a layer of coating material on its surface. The thickness of the layer of material adhering to the roller is controlled in any convenient manner, for example, by a doctor blade 15 mounted so that its edge lies close to the surface of the roller and thus permits only a selected amount of the coating material to adhere to the roller.

The sheet 16 of material to be coated is led over the surface of the roller 14 in contact therewith and picks up from the roller a film of coating material over the entire surface which contacts with the roller. Beyond the roller, the sheet passes over the edge of a doctor blade 17. This blade is formed with spaced notches 18 in its operating edge. As the coated surface of the sheet passes over the edge of the blade, the latter removes all of the film from the sheet except along lines 19 which extend in the direction of movement of the sheet. The spacing of these lines of coating depends on the spacing of the notches and the width and depth of the notches determines the amount of coating material in each line.

- The blades 15 and 17 are preferably of thin sheet metal of good heat conductivity, for example, of sheet copper $\frac{1}{8}$ " thick, and when a coating material which requires heating to become fluent is used in the apparatus, these blades are mounted in such manner as to be maintained at the same temperature as the coating material. This may be accomplished by mounting the blade so that it has a portion continuously lying within the mass of coating material or, if the tank is of metal, the blade may be mounted directly on the tank wall. The blade 17 is shown mounted in the first manner, the portion 17' lying beneath the level of the coating material 11. The blade 15 has a portion 15' resting on the top of the tank wall and held in position by bolts 20 passing through slots in the blade so as to permit adjustment of the operating edge 20 of the blade toward and away from the roller. If the heated tank is of metal, heat will pass to the blade 15 and keeps its temperature high. When the blades are mounted so that their temperature is substantially that of the coating material, the material which is scraped off the roller or the surface of the sheet, as the case may be, does not adhere to the blades but flows down them and back into the tank.
- 30 The sheet with the spaced lines of coating on it passes from the doctor blade 17 to a pair of driven pressure rolls 21. The sheet 22 to be affixed to sheet 16 is also led to the rolls and both sheets pass through the rolls together, sheet 22 being forced into contact with that face of sheet 16 on which the lines of coating material have been formed. The pressure exerted by the rolls causes the lines of coating to flatten and spread and, by proper regulation of the amount of coating applied and of the spacing of the lines by the use of a doctor blade of the desired edge configuration, just sufficient coating may be applied to give a strong bond between the sheets 45 without excess coating which would weaken the joint.

The apparatus of the invention is particularly useful in producing a metal-clad roofing consisting of a felt base and a metal layer thereon. In making such material, the metal band employed is treated in the manner of sheet 16, the felt base being united thereto in the rolls 21. However, if desired, the felt may receive the coating, though it is preferable to apply it to the metal since the latter is usually narrower than the felt and the application of the coating to the metal thus prevents the coating from reaching parts of the felt not in contact with the metal.

I claim:

1. In apparatus for coating a sheet, the combination of a tank for coating material, a roller having a portion of its periphery dipping into the coating material in the tank,

means for heating the tank, means for moving the sheet in contact with a portion of the roller above the surface of the coating material to receive a film of coating material, and a metal doctor blade engaging the sheet 70 and a substantial distance above the surface of the coating material, removing part of the film therefrom, this blade being mounted to extend below the surface of the coating material in the tank. 75

2. In apparatus for coating a sheet, the combination of a tank for coating material, a roller having a portion of its periphery dipping into the coating material in the tank, means for heating the tank, means for moving the sheet in contact with a portion of the roller above the surface of the coating material to receive a film of coating material, 80 means cooperating with the surface of the roller to regulate the thickness of said film, 85 and a metal doctor blade engaging the sheet a substantial distance above the surface of the coating material and removing part of the film therefrom, this blade being mounted to extend below the surface of the coating 90 material in the tank.

3. In apparatus for coating a sheet, the combination of a tank for coating material, a roller having a portion of its periphery dipping into the coating material in the tank, 95 means for heating the tank, means for moving the sheet in contact with a portion of the roller above the surface of the coating material to receive a film of coating material, and a metal doctor blade engaging the sheet a substantial distance above the surface of the coating material, this blade having spaced notches 100 in its operating edge and being mounted to extend below the surface of the coating material in the tank. 105

4. In apparatus of the type described, the combination of a tank for coating material, a rotary member dipping beneath the surface of the coating material in the tank, a doctor blade heated to substantially the temperature 110 of the coating material in the tank having spaced notches in its operating edge, and rotary means for moving a sheet in contact successively with said member to receive a film 115 of coating material therefrom and with said blade a substantial distance above the surface of the coating material to have said film removed except in lines spaced to correspond with said notches, said means exerting pressure serving to unite said coating sheet with another placed in contact therewith. 120

5. In an apparatus for coating a sheet, the combination of a tank for coating material, means for heating the tank, and applicator having a portion dipping into the coating material in the tank, means for moving the sheet in contact with a portion of the applicator a substantial distance above the surface of the coating material to receive a film of coating material, and a doctor blade maintained at 125

substantially the temperature of the coating material in the tank, this blade being made of thin sheet metal.

6. In an apparatus for coating a sheet, the combination of a tank for coating material, means for heating the tank, an applicator having a portion dipping into the coating material in the tank, means for moving the sheet in contact with a portion of the applicator a substantial distance above the surface of the coating material to receive a film of coating material, and a doctor blade extending below the surface of the coating material in the tank, this blade being made of thin sheet copper.

10 15 In testimony whereof I affix my signature.
